CLAIM

The ornamental design for a cuff, as shown and described.

DESCRIPTION

FIG. 1 is a top plan view of a cuff showing my new design;

FIG. 2 is a bottom plan view thereof;

FIG. 3 is a rear elevational view thereof;

FIG. 4 is a front elevational view thereof;

FIG. 5 is a left side elevational view thereof;

FIG. 6 is a right side elevational view thereof;

FIG. 7 is a top perspective view thereof;

FIG. 8 is a top perspective view thereof, with a top flap and a bottom flap opened; and,

FIG. 9 is a top perspective view thereof, with a top flap opened and a closed bottom flap.

The dotted lines in FIG. 1, 2, 7, 8 and 9 show sewing stitches.
